UNITED STATES PATENT OFFICE.

JULIA CAMPBELL, OF BATH, NORTH CAROLINA.

DESIGN FOR A BREAD-BOARD.

47,322.

Specification for Design.

Patented May 11, 1915.

Application filed March 17, 1915. Serial No. 15,083. Term of patent 7 years.

To all whom it may concern:

Be it known that I, JULIA CAMPBELL, a citizen of the United States, residing at Bath, in the county of Beaufort and State of North Carolina, have invented a new, original, and ornamental Design for Bread-Boards, of which the following is a specification, reference being had to the accompanying drawing, forming part thereof.

The figure is a perspective view of the bread board, showing my new design.

I claim:

The ornamental design for a bread board, as shown.

JULIA CAMPBELL.

Witnesses:

J. T. LINTON,
U. T. GAYLORD.
